CLAIM

The ornamental design for a base for ear cleaner, as shown and described.

DESCRIPTION

FIG. 1 is a perspective view of a base for ear cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the base for ear cleaner.
The broken lines in the drawings depict portions of the base for ear cleaner that form no part of the claimed design.

1 Claim, 9 Drawing Sheets
